UNITED STATES PATENT OFFICE

ANSON J. FROST, OF SPOKANE, WASHINGTON

ELECTRIC INSECT DESTROYER

Application filed July 9, 1926. Serial No. 121,478.

This invention relates to electric insect destroyers of the general type, especially where used in doors or window sashes for screening and protecting buildings against insects, wherein a plurality of lengths of electrically charged wires of alternate polarity are disposed adjacent and parallel to each other in such a manner that the insects will be electrocuted by completing or closing the normally open circuit that is maintained, the current reaching the adjacent wires through the bodies of the insects that come in contact with, or in close proximity to, said wires.

The invention relates more particularly to insect destroyers of the general type in which two wires are employed which extend parallel and adjacent to each other throughout the length or width of the supporting frame on which electrical connections are mounted on parallel insulating strips along the edges of the supporting frame to which said wires are secured by either being provided with a number of reverse bends, or by being led across the frame in opposite directions, or in serpentine or zig-zag fashion.

In a device of this character it is absolutely essential that the wires be properly insulated from each other, as well as from the supporting frame, and that the insulating material used be of such form and composition as to be of sufficient strength and electrical resistance, and to also be of such character as to permit the device to be readily and economically manufactured. It is also desirable that the insulation strips used be centrally disposed on the inner edges of the supporting frame in order to prevent the tension of the wires from twisting or warping the frame or sash.

Under these circumstances, the principal objects of my invention are to furnish an electric insect destroyer provided with a suitable form of insulating and supporting material permitting rapid and economical manufacture and which will also constitute an improved means for insulating the parallel lengths or runs of wire forming the energized grid from each other and which will also rigidly support and insulate the wires from the supporting frame or sash. A further object of this invention is to furnish an insulating strip

to be centrally disposed on the inner edge of the sash or frame, thereby preventing the warping or distortion of the sash through the tension of the wires. Another object of the invention is to produce an insulating strip of such form as to admit of rapid and economical manufacture of electric insect destroyers of the type indicated.

The novel device by which the invention is carried out will appear fully from the description and claims.

In the drawings, wherein the numerals refer to the same parts throughout the views,

Fig. 1 is a plan view, somewhat in perspective, showing my invention applied to a screen frame,

Fig. 2 is a detail plan view showing a portion of the insulating strip used in the Fig. 1 form of device,

Fig. 3 is a detail plan view showing a portion of a modified form of insulating strip,

Fig. 4 is a view similar to Fig. 3, showing a second modified form of insulating strip,

Fig. 5 is a transverse sectional view taken through one side of the frame shown in Fig. 1, and

Fig. 6 is a sectional view showing the method of attaching an insulating strip of my invention to a metallic screen frame.

Referring to Fig. 1, the letter A indicates a wooden sash frame provided with insulating strips 1 and 2 upon the inner sides of its side members. The insulating strip 2 is shown enlarged in Fig. 2 and is provided with two rows of substantially U-shaped slots or cuts b and b', respectively, the slots b being staggered with respect to the slots b'. It will be seen that a wire 3 of negative polarity can be threaded into one of the slots b' and pulled down into the end of one of the extremities of the slot and then passed across and threaded into the other extremity of the same slot. Negative wires 3 would be threaded in the slots b' and positively charged wires 4 would be threaded in slots b, or vice versa.

The insulating strip 1 shown in detail in Fig. 3 and used on the other side of frame A is generally similar to strip 2 except that it is designed to facilitate the placing of the wires in the screen. To this end, a transverse slot

D extends from the inner edge of the strip and through the bight portion of each of the slots b and thence to the bight portion of the slots b'. This transverse slot D of course permits the wire to be quickly placed in the desired slot, either b or b' and hence facilitates assembly of the screening.

The strip shown in Fig. 4 is also intended to facilitate assembly and it comprises two rows of right-angled slots b and b', staggered and oppositely arranged, having their adjacent ends connected by a transverse slot extending to the edge of the strip. Positive wires 4 could be placed in the slots b and negative wires 3 in the slots b'.

Strips of the forms shown in Figs. 2, 3 or 4 may be used either in pairs or two strips of one of these three types may be used as a pair.

A method of securing the insulated wires supporting strips in a wooden frame is shown in Fig. 5. It will be seen that the frame need only be slotted on its inner side and the strip 1 or 2 placed in this slot and secured by a screw C. The strip of course prevents the frame from warping and otherwise reinforces it. The strips can be secured in a metal frame in the manner shown in Fig. 6, the strip being placed between the frame C', and a plate d and the frame C', strip 1 and plate d riveted or otherwise secured together.

It will be seen from the above that the wires 3 and 4 will be spaced equidistant from each other throughout their respective lengths and will be so closely spaced as to prevent insects from passing between them without touching both wires and thus completing the circuit and being electrocuted. Current can be supplied the wires from any suitable source.

40 I claim:

1. An electric insect destroyer comprising a frame, insulating strips at the opposite sides of said frame, each of said strips being provided with two rows of slots, the slots of one row being staggered with respect to the slots of the other row, said strips being provided with slots extending from one edge of the strips and through a slot in each of the rows of slots and wires supported in said first 50 named slots.

2. An electric insect destroyer comprising a frame, insulating strips at the opposite sides of said frame, each of said strips being provided with two rows of angled slots, the slots of one row being staggered with respect to the slots of the other row, said strips being provided with slots extending from one edge of the strips and through a slot in each of the rows of slots and wires supported in said first 60 named slots.

3. An electric insect destroyer comprising a frame, insulating strips positioned on opposite sides of said frame, each of said strips having a row of slots therein, each slot having a pair of branch slots at an angle thereto.

and terminating within the margin of the strip, and wires engaged and supported in the ends of pairs of said branch slots.

4. An electric insect destroyer comprising a frame, insulating strips positioned on opposite sides of said frame, each of said strips having a series of slots therein, each slot comprising a pair of substantially parallel slots and a transverse connecting slot, and continuous conducting wires having loops engaged in pairs of said transverse slots.

5. An electric insect destroyer comprising a frame, insulating strips positioned on opposite sides of said frame, each of said strips having a series of slots therein, each slot comprising a pair of substantially parallel slots and a transverse connecting slot, and continuous conducting wires of opposite polarity disposed in alternate parallel relation across the frame, adjacent lengths or runs of said wires being connected by loops or return bends, each loop being engaged and supported in a pair of said transverse slots.

6. An electric insect destroyer comprising a frame, insulating strips positioned on opposite sides of said frame, each of said strips having a series of angled slots providing a series of parallel wire-retaining tongues, and wires engaged in the angles of the slots and retained in position by said tongues.

7. An electric insect destroyer comprising a frame, insulating strips positioned on opposite sides of said frame, each of said strips having a series of angled slots therein providing a series of parallel wire-retaining tongues, and continuous conducting wires of opposite polarity disposed in alternate parallel relation across the frame, adjacent lengths or runs of said wires being connected by loops or return bends, each loop being engaged in the angles of said slots and retained in position by said tongues.

In testimony whereof, I affix my signature.
